[57] CLAIM

The ornamental design for a switch housing for providing various different functions to keys of a single key pad, as shown and described.

DESCRIPTION

FIG. 1 is a perspective view of a switch housing for providing various different functions to keys of a single key pad.

FIG. 2 is a top plan view of the invention;

FIG. 3 is a bottom plan view of the invention;
FIG. 4 is a right side elevational view of the invention;
and,

FIG. 5 is a rear elevational view of the invention.
The broken line showing in FIGS. 1-4 is included for the purpose of illustrating environmental structure only and form no part of the claimed design.

FIG. 1

FIG. 2

FIG. 3

FIG. 4

FIG. 5
